UNITED STATES PATENT OFFICE

OTTO J. GROEHN, OF DETROIT, MICHIGAN, ASSIGNEE TO BRISCOM MANUFACTURING COMPANY, OF DETROIT, MICHIGAN, A CORPORATION OF MICHIGAN.

METHOD OF BENDING METAL.

1,158,484.

Specification of Letters Patent.

Patented Nov. 2, 1915.

Application filed June 8, 1912. Serial No. 702,479.

To all whom it may concern:

Be it known that I, OTTO J. GROEHN, a citizen of the United States of America, residing at Detroit, in the county of Wayne and State of Michigan, have invented certain new and useful Improvements in Methods of Bending Metal, of which the following is a specification, reference being had therein to the accompanying drawings.

10 The invention relates to the art of forming metal, and it is the particular object of the invention to facilitate the bending of flat blanks edgewise or in the plane of the strip.

To this end the invention consists in the novel method as hereinafter set forth.

In the drawings: Figure 1 is a perspective view of the blank. Fig. 2 is a similar view after the first operation. Fig. 3 is an elevation illustrating the bent portion. Fig. 4 is 20 a cross section of Fig. 3. Fig. 5 is a perspective view of a bent strip. Fig. 6 is a cross section through a modified form of blank.

25 For many uses—such for instance as in the formation of automobile fenders and similar articles, it is necessary to form sheet metal strips by bending the same edgewise. Such an operation is, however, difficult to perform without causing the buckling or 30 wrinkling of the blank, and, as heretofore accomplished, has required complex and expensive machines or gigs. By my improved method a blank may be bent, without wrinkling, to any form or curve either continuous or changing that may be desired, by an 35 exceedingly simple operation and by the use of simple tools.

The essential feature of my method is the holding of the opposite edges of the blank 40 from being drawn toward each other during the edgewise bending of the strip. This is accomplished by forming opposed shoulders respectively adjacent to said opposite edges, and which may be engaged by the forming 45 tool as hereinafter described.

A suitable sheet metal blank, such as A, Fig. 1, is first provided with the opposed shoulders, preferably by bending reverse hooks B and C in the marginal portion of 50 the metal. When thus formed the strip is bent edgewise by passing through rolls or dies which simultaneously engage and hold apart the opposite hooks and also retain the intermediate metal from buckling. Fig. 3

shows diagrammatically a machine which 55 may be employed for this bending operation, in which D D' E E' F F' are pairs of forming rolls. Each roll preferably comprises a disk-shaped portion G, the periphery of which engages the inner face of one of the 60 hooks B or C; also a grooved portion H for engaging the outer face of the opposite hook. The co-operating roll is of similar shape, the disk portion engaging the inner face of the hook which is in engagement with the groove 65 of the first-mentioned roll. Thus the sheet metal is held between the flat adjacent faces of the two disk portions of the rolls, while the peripheral engagement of the disks with the hooks holds the latter from inward 70 movement.

To form a strip to any desired contour, it is merely necessary to relatively move the pairs of rolls. For instance, if the central rolls E E' are raised or lowered with respect 75 to the outer rolls, this will cause a change in the curvature of the bend, and by controlling the movement of this pair of rolls by suitable means—such as a cam I—any curve may be obtained. As shown in Fig. 5 80 the strip is bent with reverse curves.

While I have described the bending of the reverse hooks upon the opposite edges of the blank it is obvious that other means of forming the opposed shoulders can be used, 85 such for instance as using a blank shown in Fig. 6, the marginal portions J of which are thickened to form the reverse shoulders K and K'.

What I claim as my invention is:

1. The method of bending flat blanks in the plane thereof, which consists in bending hook flanges at the opposite edges thereof, in engaging the opposite sides of the intermediate portion of the blank to prevent side- 95 wise movement thereof, engaging said hook flanges to hold the same from movement toward each other, and in bending the blank edgewise while thus held.

2. The method of bending flat blanks in 100 the plane thereof, comprising the bending of hook flanges upon opposite edges of the blank, in engaging the flat faces on opposite sides of the blank to hold the same from side- 105 wise movement, and in engaging the hook flanges to hold the same from movement toward each other while relatively varying the curve of the bend.

3. The method of bending flat blanks in the plane thereof, which consists in forming hook flanges in the opposite edges of the blank, in bending the blank edgewise while 5 engaging the opposite sides of the flat faces thereof, in holding the hook flanges, and in varying the curve of the bend.

In testimony whereof I affix signature in presence of two witnesses.

OTTO J. GROEHN.
